UNITED STATES PATENT OFFICE

2,179,486

RELAY

Charles M. Barnes, Arlington, Va.

Application August 9, 1938, Serial No. 223,939

3 Claims. (Cl. 200—106)

(Granted under the act of March 3, 1883, as
amended April 30, 1928; 370 O. G. 757)

This invention relates to an electric relay and has for an object to provide an improved relay sensitive to extremely small currents.

A further object of this invention is to provide
5 a relay which may be adjusted to either of two
positions, in one of which the relay will auto-
matically reset itself as often as desired, and in
the other of which the relay will remain in con-
tinuous operation once it is operated until it is
10 manually reset.

With the foregoing and other objects in view, the invention consists in the construction, combination and arrangement of parts hereinafter described and illustrated in the drawing, in which,

Fig. 1 is a schematic view of the relay adjusted for non-resetting position; and

Fig. 2 is a similar view of the relay adjusted for resetting position.

20 Many uses are possible with this invention but it is here illustrated as being adjusted for two possible uses, one use being to indicate that a door has been opened and thus actuate a burglar alarm continuously even though the door has
25 been closed again, and in the other use it is shown as merely indicating that the door is open or shut.

In the first use, shown in Fig. 1, a closed circuit 10 is connected through a door 11 and a current supply 12 to energize a solenoid 13 having an armature 14 held thereagainst so long as the closed circuit 10 is unbroken while the door 11 remains closed. The armature 14 is mounted at an angle 22 on the end of a bent lever 15 extending from an arm 16 pivoted as at 17. A switch lever 18 pivoted as at 19 is provided at one end with a roller 20 which presses against the under side of the bent lever 15 while the armature 14 is in position against the solenoid 13. The other end of lever 18 is provided with a strong spring 21 urging the roller 20 on the end of lever 18 beyond the angle 22 connecting the lever 15 and armature 14. Also carried by the end of the lever 18 adjacent the spring 21 is an electric contact 23 adapted to be closed against the contact 24 and thus actuate an alarm bell or other indicating means 25 when the circuit through the solenoid 13 is broken by the door 11 being opened and the lever 18 being urged by the spring 21 to the position shown against the stop 26 mounted in the

If the lever 15 and armature 14 are in such a position that gravity will not normally return the armature 14 to the position adjacent the solenoid 13, then a weak spring 28 may be attached to the

end of the arm 16, the spring 28 being considerably weaker than the spring 21 so that it will not interfere with the operation of the spring 21. As thus adjusted once the door 11 is opened an alarm or indicator 25 will be actuated and remain in operation, irrespective of the door 11 being reclosed, until the relay lever 18 is manually reset by being drawn away from the stop 26 removing the roller 20 to the other side of the angle 22 between armature 14 and lever 15.

If it is desired to use the alarm bell or indicator 25 as merely a signal indicating whether the door 11 is open or shut, then stop 26 will be adjusted so as to be mounted in position 29. In this position, as illustrated in Fig. 2, the roller 20 will not go beyond the angle 22 when the door 11 is opened, the contacts 23 and 24 being adjusted if necessary so as to complete the circuit before the roller 20 has passed angle 22. As thus shown in Fig. 2, reclosing the door 11 will complete the circuit through circuit 10 and actuate the solenoid 13 to draw armature 14 thereagainst and break the circuit between contacts 23 and 24, thus resetting the relay and stopping the operation of the indicator 25, showing that the door 25 has been reclosed. 15 20

Other modifications and changes in the proportions and arrangements of the parts may be made by those skilled in the art without departing from the nature of the invention, within the range of what is hereinafter claimed. 30

The invention described herein may be manufactured and used by or for the Government of the United States of America for governmental purposes without the payment of any royalties thereon or therefor. 35

Having thus set forth and disclosed the nature of this invention, what is claimed is:

1. An electric relay comprising a solenoid, an armature for said solenoid, a pivoted bent lever 40 on which said armature is mounted at an angle, a pivoted switch lever having one end in contact with the bent lever mounting of said armature and carrying a circuit closing contact at its other end whereby said switch lever may close the circuit when said armature is released by said solenoid, and stopping means limiting the travel of the free end of the switch lever along said armature mounting lever, said stopping means stopping the free end of the switch lever before it reaches the angle in the mounting lever whereby the solenoid may reattract the armature to reset the relay. 45 50

2. An electric relay comprising a solenoid, an armature for said solenoid, a pivoted bent lever 55

- on which said armature is mounted at an angle, a pivoted switch lever having a free end in contact with the bent lever mounting of said armature and carrying a circuit closing contact at its other end whereby said switch lever may close the circuit when said armature is released by said solenoid, and stopping means limiting the travel of the free end of the switch lever along said armature mounting lever, said stopping means 5 stopping the travel of the free end of the switch lever after it has passed the angle between the armature and the mounting lever to block off the return of the armature to the solenoid until the switch lever has been manually reset.
- 10 15 3. An electric relay comprising a solenoid, an armature for said solenoid, a pivoted bent lever on which said armature is mounted at an angle, a pivoted switch lever having a free end in contact with the bent lever mounting of said arma-

ture and carrying a circuit closing contact at its other end whereby said switch lever may close the circuit when said armature is released by said solenoid, and stopping means adjustable to either of two positions limiting the travel of the free end of the switch lever along said armature mounting lever, said stopping means when adjusted in one position stopping the free end of the switch lever before it reaches the angle in the mounting lever whereby the solenoid may retract the armature to reset the relay, said stopping means when adjusted in the other position stopping the travel of the free end of the switch lever after it has passed the angle between the armature and the mounting lever to block off the return of the armature to the solenoid until the switch lever has been manually reset. 10 15
